(57) CLAIM

The ornamental design for a desk organizer, as shown and described.

DESCRIPTION

FIG. 1 is a perspective view of a desk organizer showing our new design;

FIG. 2 is another perspective view thereof;

FIG. 3 is a front view thereof;

FIG. 4 is a back view thereof;

FIG. 5 is a side view thereof, the opposing side being a mirror image;

FIG. 6 is a bottom view thereof; and,

FIG. 7 is a top view thereof.

The broken lines shown in the drawings are included for purposes of illustrating environment and form no part of the claimed design.
